SHOWER-PIPE FOR PAPER-MAKING MACHINES.

1,180,807.

Specification of Letters Patent. Patented Apr. 25, 1916.

Application filed November 27, 1915. Serial No. 63,857.

To all whom it may concern:

Be it known that I, JOHN WARREN VEDDER, a citizen of the United States of America, and a resident of Wilmington, Delaware, have invented a new and useful Improvement in Shower-Pipes for Paper-Making Machines, which invention is fully set forth in the following specification.

The present invention is an improvement 10 in wash or so-called "shower" pipes which are particularly designed for use in cleansing various parts of paper-making machinery, such as the Fourdrinier wire, felt conveyers, rolls and the like; and the objects of the invention, among others, are to 15 provide a highly efficient, durable and simple device of this character, which will throw an unbroken sheet of water or liquid of substantially uniform force and velocity along 20 the line where it strikes the Fourdrinier wire, felt, roll, or other body to be cleansed, the effective velocity for a given water pressure being greater than any heretofore attained; and to provide a shower pipe which, 25 while producing a sheet of high and substantially uniform velocity throughout, will also be economical in the use of water.

Absolute cleanliness of the parts of a paper-making machine—particularly at the 30 Fourdrinier end thereof—is a *sine qua non* of perfect paper; and hence it is quite necessary to remove from the parts to be cleaned all fibers, foreign substances contained in the pulp, etc. Aside from this 35 matter of preventing impurities from getting into the paper, it is absolutely necessary to wash all of the stock from the Fourdrinier wire throughout its width before the same passes over the first wire-supporting 40 roll after the wire has passed the bottom couch roll; for, if a narrow strip of the pulp were to pass around the bottom couch roll and was not washed off of the wire before it reached the first wire-supporting roll, 45 it would adhere to said wire-supporting roll and, in a very few minutes (the Fourdrinier wire on a modern paper-making machine travels up to 700 feet per minute), would wind up on said roll to an extent sufficient 50 to break or rupture the Fourdrinier wire. When it is considered that the normal life of such a wire is only two or three weeks, and that such a wire costs between two and three hundred dollars, it is appreciated that this

matter of washing by means of an efficient 55 "shower" pipe is of prime importance.

It is pointed out that the velocity of the unbroken sheet and the volume of water used with a given unit length of shower pipe depend primarily upon the water pressure and 60 quantity of water available. The pressures in the usual mill vary between ten and forty pounds, and it is practically always necessary to secure the maximum velocity with such low pressures. Further, a shower pipe 65 that was otherwise efficient but was wasteful of, or in other words, used too much, water, would have little commercial availability, for the reason, among others, that the water thus used would dilute the stock, 70 clay, and sizing to a degree that would prevent economical handling; and the recovery of the stock washed from the wire is economically necessary. It is therefore desired 75 to use the minimum volume of fluid that will do the work and, with the pressures usually available at mills, at the maximum effective velocity at the point of work; and the device of the present invention is adapted for 80 this purpose.

Briefly stated, these objects are attained by causing the streams of liquid that pass through a row of perforations, nozzles, or orifices, longitudinally arranged along a pipe, to impinge or hit against similar 85 streams passing through a second row of orifices longitudinally arranged along the pipe, one orifice of each row being arranged in the same transverse plane as an orifice in the other row, and said orifices being so 90 spaced that the liquid of the various streams will merge or be converted into a single unbroken sheet of liquid midway between the rows of orifices and radial to the pipe and of substantially equal strength throughout. 95

To secure the best results, it is necessary to have each pair of nozzles deliver the same volume of water, and therefore the nozzles must be kept clean and open. Accordingly, a further object of the present invention is 100 to provide an improved cleaning device for the shower pipe, said cleaning device being mounted on the valve stem which controls the outlet. The result of this is that the swabbing or clearing action cannot be 105 started until the wash-out valve is open, thus causing all dirt removed to flow through the outlet rather than through the perforations

or nozzles, which latter would either tend to cause the perforations or nozzles to clog up or, failing to do this, the dirt would pass out into the paper which is equally, if not 5 more, objectionable.

The invention will be better understood by reference to the accompanying drawings, wherein—

Figure 1 is a longitudinal sectional view 10 through a preferred form of shower pipe and its end fittings embodying the present invention; Fig. 2 is a cross-section through a pipe circular both inside and outside, to which two perforated strips are brazed or 15 soldered; Fig. 3 is a similar view of a pipe to which perforated buttons are secured; Fig. 4 is a face view of one of said buttons; Fig. 5 is a similar view of a pipe to which a single perforated strip is soldered or 20 brazed; Fig. 6 is a face view of, and Fig. 7 a cross-sectional view through, a shower pipe, such as is shown in Fig. 1, provided on the exterior with an integral rib in which the orifices or perforations may be formed. 25 Fig. 8 is a sectional view through a nozzle or perforation in the form of a Borda mouth-piece; and Fig. 9 is a similar view through a perforation or orifice in the form of a Venturi nozzle.

Referring to the drawings, wherein like 30 reference numerals indicate like parts, 12 indicates a shower pipe, preferably formed of extruded metal, to one extremity of which is secured in any suitable manner, as by 35 screw-threaded engagement, a T end-fitting 13 provided with an opening 14 in which is secured a suitable conduit (not shown) leading to a water or other liquid supply. At 40 its other end said pipe 12 engages an end fitting 15 which accommodates a suitable valve 16, which valve is normally seated to prevent the liquid from passing out through a waste passage 17 in said fitting. The 45 liquid is thus normally forced to pass out of pipe 12 through two rows of perforations 18 and 18' arranged longitudinally of said pipe.

Heretofore it has been usual to provide a 50 single row of perforations arranged longitudinally of the pipe through which the streams of water passed directly to the wire or other body to be cleansed. In such a construction the nozzles or perforations were spaced about one inch apart. It has also been 55 usual heretofore to project the water from such a single row of perforations against a stationary lip or "splatter board," as in the patent to Millspaugh, No. 782,755, dated February 14, 1905, thus converting the several streams into a single sheet. In such a 60 construction the nozzles or perforations could be spaced about three inches apart. This "splatter board" construction while possessing some advantages was found to 65 largely reduce the efficiency of the pipe, the

velocity of the water being reduced when it impinged against the lip or "splatter board." This is a matter of great importance for, in the average mill, the water pressure is between ten and forty pounds, and to clean 70 effectively and efficiently the wire and other parts, it is usually necessary to utilize every ounce of pressure available.

It has been discovered that, if the streams of water or other liquid passing through one 75 longitudinal row of perforations, orifices or nozzles, as 18, impinge or hit against the streams from corresponding orifices, as 18', similarly arranged, and at not too obtuse an angle, the speed of travel of the streams 80 passing through each longitudinal row of orifices being the same, practically none of the velocity of the streams will be dissipated; and, for a given water pressure, the velocity and force of the unbroken sheet of 85 liquid as it acts on the body to be cleaned will greatly exceed that heretofore attained.

The formation of such an unbroken sheet of water requires a certain angular relation of the perforations of one series with 90 respect to those of another. Further, in order that the streams from any given pair of nozzles shall exactly and squarely impinge upon each other, it is necessary that they have certainty of direction; and, to this 95 end, the perforations or nozzles must have a bore of sufficient length to give the streams the necessary direction or aim.

It has been experienced that there is a limitation of the angular relation of each 100 pair of orifices. If, for example, orifices 18 and 18' were arranged at as great an angle as 120°, there would be no sheet formation at any practical working pressure, but only a fine spray would be produced. To secure 105 this unbroken sheet formation, it has been found that each pair of orifices 18 and 18' should be arranged at from 45° to 60° at working pressures of from ten to forty pounds. Variations between these limits 110 may be had depending upon the water pressure available, the nearness of the shower pipe to the wire or felt and the spacing of the orifices.

It has further been found by experiment 115 that a bore of less than two diameters is too short; and that it will not continue to give, under working conditions, the direction or aim which is absolutely necessary, for the reason that the water used is not perfectly 120 clean and free from solid or fibrous matter which more easily diverts or misdirects the streams from short-bored nozzles or orifices than from long ones of three diameters or more. Preferably the length of each bore is 125 three diameters or more, in order that this directing or aiming action may be effectively secured.

It has been discovered that there is a 130 slight tendency for the effective velocity and

force of each fan-like stream to diminish toward the end of the spread. This is overcome by so spacing the perforations 18 and 18' as to cause the fan-like streams to overlap one another (as particularly indicated at *a*, Fig. 1), the overlapping or merging of the less forceful marginal portions of the streams producing a continuous sheet or body of water having a velocity and force 10 approximately equally distributed along the line of contact with the body to be cleansed. By way of example, it may be noted that desirable results have been secured with orifices from $5/64''$ to $7/64''$ in diameter, the 15 included angles of the orifices being from 45° to 60° and spaced from $2\frac{1}{2}''$ to $3\frac{1}{2}''$ apart in each row. With this arrangement there has been secured uniform velocity or force 20 at the point where the water strikes the wire or other body. As shown in the drawings, the nozzles are arranged so that the periphery of each orifice just touches the periphery of its companion orifice in the other row. This arrangement may, however, be 25 varied within limits, and under certain conditions it has been found desirable to space the nozzles about one diameter apart. Holes of $6/64''$ in diameter, with an included angle of 55° and no distance apart have been 30 found to give very good results at the low pressures used in most mills; that is to say, between ten and forty pounds. The spacing apart and the angular relation of the nozzles with respect to each other, determine 35 the amount of spread which is given to each stream for a given pressure. Whereas an acute angle makes for less spread and greater velocity, an obtuse angle makes for more spread and less velocity. It is therefore 40 pointed out that, for a certain minimum orifice diameter which would be practically available, it is desirable to use as wide a spacing as is possible to secure the desired spread with a suitable resultant or 45 consequent velocity.

Figs 1, 6 and 7 illustrate the preferred embodiment of the inventive idea. As therein shown, the perforations of orifices 18 and 18' are arranged in an integral ribbed portion 50 of the pipe, each pair being disposed in the same transverse plane as heretofore stated. The rib 19 is provided with two faces 20 and 20', angularly disposed with respect to each other, and the orifices 18 and 18' are arranged at between 45° and 60° , as hereinbefore stated. The sheet of liquid 55 thus produced is of substantially uniform flow both in volume and velocity.

Various other constructions of shower 60 pipes may be employed to secure the objects and benefits of the invention. In Fig. 2 the pipe 12 is shown circular both inside and outside, with two strips 21 and 22 suitably secured thereto, as by brazing or soldering. 65 Perforation 18 passes through strip 21 and

the wall of the pipe, and perforation 18' through strip 22 and the wall of the pipe.

In Figs. 3 and 4, the perforations 18 and 18' are formed in buttons 23 that are inserted in circular openings in the pipe 12, 70 and suitably secured in place in any desired manner. Each button is provided with a flange 24 that engages the outside face of the pipe around its opening.

The spacing apart of the jets or nozzles in 75 each row, together with the diameter, area and type of nozzle employed (whether standard tube, Borda mouth-piece, Venturi nozzle, etc.), affects the volume of liquid ejected per unit of length. And the inventive idea 80 may be embodied in various structures having perforations delivering liquid in varying volume and at varying velocities, the desired velocity and volume being affected by the shape of the perforations or nozzles. If, 85 with a given water pressure, a very high velocity is desired, this can be secured by the use of orifices shaped like a Borda mouth-piece (see Fig. 8); and if, on the other hand, large volume and not high velocity is 90 desired, an orifice or nozzle with a diverging bore like a Venturi nozzle, would be employed, as shown in Fig. 9.

Whatever the shape and cross-sections of the orifices may be, however, the bore or 95 length of the orifices should be at least twice—and preferably more than three times—its diameter, in order that perfect aim and direction be secured; and the nozzles or orifices should have the angular relation and spacing above indicated. 100

Inasmuch as each stream impinges against another moving stream traveling at the same speed, practically all tendency toward diminution of velocity is obviated. The result 105 of this, as heretofore stated, is that, with a given water pressure, the sheet of water that strikes the surface to be cleaned will have greater force and velocity than it has been possible to obtain heretofore from the same 110 supply pressure. A further important result is that, inasmuch as deflecting lips and flanges are eliminated, a cheaper, simpler, better and more efficient device in every respect is produced. 115

It is highly desirable that an efficient cleaning device for the pipe be provided, in order that the nozzles or orifices 18 and 18' may be kept clean and open, to insure that each pair of nozzles shall deliver the same 120 quantity of liquid. This cleaning device is arranged so that accumulations will be removed through the waste passage 17 rather than through said nozzles.

As heretofore stated, valve 16, which is 125 preferably of rubber, is normally seated to prevent the liquid from passing through passage 17, and this valve is carried by a hollow stem 28. Preferably, the valve 16 is mounted on a movable holder 29 that is slid- 130

able in the end of stem 28, a spring 30 bearing at one end against said holder and at its other end against an abutment 31 secured to the stem 28 by any suitable means, as a pin or rivet 32. This pin or rivet 32 also secures in place on stem 28 a cleaning device having an annular scraping member 33 which is connected by ribs 34 to a central portion 35 through which the pin or rivet 32 passes (Fig. 1). The function of the spring 30 is to keep the valve 16 seated if, due to changes in temperature, for example, a difference in the relative length of pipe 12 and tube 28, should occur. Under certain working conditions, such change in length might not occur and, in that case, an ordinary non-yielding form of valve might be used.

It will be understood that, when it is desired to clean the pipe, the stem 28 is reciprocated to move the scraping surface 33 along the pipe, thus dislodging any accumulations which are promptly washed out through the waste opening 17, the valve 16 being removed from its seat at this time.

With the device shown in Fig. 1, the valve 16 is normally held seated by means of spring 30 and the engagement of a coarse pitch thread 37, formed on the stem 28, with a corresponding screw-threaded opening in yoke 38 formed on the T-fitting 13, stem 28 being moved by a suitable handle 39 formed thereon. During the normal operation of the device, the pressure of the water tends to keep the valve 16 seated.

The arrangement of the cleaning device so that it will move with the valve and valve stem is very important as the cleaning action cannot be started until the wash-out valve 16 is opened, whereby all dirt or accumulations are caused to flow out through the passage 17 and not attempt to escape through the orifices 18 or 18'. This prevents these orifices from being clogged up or, what is, if anything, more objectionable, having the dirt or accumulations pass out through said orifices and into the paper, thus injuring the same.

While for the purpose of illustration, various embodiments of the inventive idea have been shown and described in detail, it is to be understood that the invention is not limited to the structures illustrated, but that the inventive idea is susceptible of various other mechanical expressions within the limits of the appended claims.

This application constitutes a continuation of my copending application for shower pipes, Serial No. 848,416, filed July 1, 1914, 60 as concerns such subject matter as is common to the two applications.

What is claimed is:—

1. A shower pipe for paper-making machines having two rows of perforations projecting streams of liquid, the streams from

one row of perforations impinging upon the streams from the other row of perforations thereby converting the streams into a sheet, the said perforations being spaced apart equal distances and so arranged that the less forceful marginal portions of the streams overlap whereby there is produced a sheet of liquid of substantially uniform velocity and force throughout. 70

2. A shower pipe for paper making machines provided with two longitudinal series of perforations, one perforation of each series being arranged opposite a corresponding perforation in the other series and at an angle of not less than 45° and not more than 60°, and each perforation having a length not less than twice its diameter, said perforations in each series being equally spaced apart longitudinally and so arranged that the less forceful marginal portions of the streams overlap whereby there is produced a sheet of liquid of substantially uniform velocity and force throughout. 80

3. A shower pipe for paper making machines provided with two rows of oppositely disposed perforations, each perforation having a length not less than twice its diameter and being arranged at an angle of not less than 45° and not more than 60° to its corresponding perforation, said perforations being equally spaced apart longitudinally and so arranged that the less forceful marginal portions of the streams overlap whereby there is produced a sheet of liquid of substantially uniform velocity and force throughout. 90

4. A shower pipe for paper making machines provided with two rows of oppositely disposed perforations, each perforation having a length not less than twice its diameter and being arranged at an angle of not less than 45° and not more than 60° to its corresponding perforation, the said perforations being equally spaced apart longitudinally and so arranged that the less forceful marginal portions of the streams overlap whereby there is produced a sheet of liquid of substantially uniform velocity and force throughout, the discharge ends of each pair of perforations being not more than one diameter apart. 105

5. A wash or so-called "shower" pipe for paper making machines provided with two rows of oppositely disposed nozzles, and each nozzle being angularly arranged with respect to its companion nozzle in the other row and having a length not less than twice its diameter, the said perforations being equally spaced apart longitudinally and so arranged that the less forceful marginal portions of the streams overlap whereby there is produced a sheet of liquid of substantially uniform velocity and force throughout. 120

6. A wash or so-called "shower" pipe for 130

- paper making machines provided with two rows of oppositely disposed nozzles, and each nozzle being angularly arranged with respect to its companion nozzle in the other 5 row and having a length not less than twice its diameter, the discharge ends of each pair of nozzles being separate and not more than one diameter apart, the said perforations being equally spaced apart longitudinally 10 and so arranged that the less forceful marginal portions of the streams overlap whereby there is produced a sheet of liquid of substantially uniform velocity and force throughout.
- 15 7. A straight wash or so-called "shower" pipe for paper-making machines provided with two longitudinal rows of equally spaced nozzles one nozzle in each row being in the same transverse plane as a nozzle in 20 the other row and angularly arranged with respect thereto whereby streams issuing from each pair of nozzles will impinge upon each other and spread out in fan-like formation, said nozzles being so positioned 25 longitudinally that the less forceful marginal portions of each fan-like formation will overlap and strengthen the marginal portions of adjacent fan-like formations thus producing a sheet of fluid of substantially equal strength and velocity throughout at the point where it engages the body 30 to be cleansed.
8. A straight wash or so-called "shower" pipe for paper-making machines provided 35 with two longitudinal rows of equally spaced nozzles one nozzle in each row being in the same transverse plans as a nozzle in the other row and angularly arranged with respect thereto whereby streams issuing 40 from each pair of nozzles will impinge upon each other and spread out in fan-like formation, said nozzles being so positioned longitudinally that the less forceful marginal portions of each fan-like formation 45 will overlap and strengthen the marginal portions of adjacent fan-like formations thus producing a sheet of fluid of substantially equal strength and velocity throughout.
- out at the point where it engages the body to be cleansed, the discharge ends of each 50 pair of nozzles being not more than one diameter apart.
9. A shower pipe for paper making machines provided with an inlet and an outlet, a spring-pressed valve normally closing said 55 outlet, a stem on which said valve is mounted, and a hollow cylindrical cleaning device carried by said stem.
10. A shower pipe for paper making machines provided with an inlet and an outlet, 60 a spring-pressed valve normally closing said outlet, a stem on which said valve is mounted, and a cleaning device carried by said stem.
11. A shower pipe for paper making machines provided with an inlet and an outlet, 65 a valve normally closing said outlet, a stem on which said valve is mounted, and into which the valve has a lost motion connection, and a scraping device for said pipe carried by said stem.
12. A shower pipe for paper making machines provided with an inlet and an outlet, a spring-pressed valve normally closing said 70 outlet, a stem on which said valve is mounted, a scraping device for said pipe carried by said stem, and means comprising screw threads on the stem for holding said stem in place.
13. A shower pipe for paper making machines provided with an inlet and an outlet, 75 a spring-pressed valve normally closing said outlet, a stem on which said valve is mounted, and a hollow cylindrical cleaning device movable with said valve.
14. A shower pipe for paper making machines provided with an inlet and an outlet, a valve normally closing said outlet, a stem on which said valve is mounted, and with which the valve has a lost motion connection, and a scraping device for said pipe movable with said valve.
- In testimony whereof I have signed this specification.

JOHN WARREN VEDDER.
